UNITED STATES PATENT OFFICE.

CLARENCE E. SWEENEY, OF RIDGEWOOD, NEW JERSEY.

DESIGN FOR A PRINTED FABRIC.

Application filed September 29, 1927. Serial No. 23,576. Term of patent 3½ years.

To all whom it may concern:

Be it known that I, CLARENCE E. SWEENEY, a citizen of the United States, and a resident of Ridgewood, in the county of Bergen and State of New Jersey, have invented the new, original, and ornamental Design for a Printed Fabric, of which the following is a specification.

Reference is to be had to the accompanying drawing in which the figure is a view

of a swatch of fabric illustrating the new design.

What is claimed is—

The ornamental design for a printed fabric as shown.

Signed at New York, in the county of New York and State of New York this 17th day of September A. D. 1927.

CLARENCE E. SWEENEY.
